UNITED STATES PATENT OFFICE.

FRANCIS H. SHEPARD, OF NEW ROCHELLE, NEW YORK, ASSIGNEE TO WESTINGHOUSE ELECTRIC AND MANUFACTURING COMPANY, A CORPORATION OF PENNSYLVANIA.

CONTROL SYSTEM.

1,260,721.

Specification of Letters Patent. Patented Mar. 26, 1918.

Application filed December 26, 1913. Serial No. 808,734.

To all whom it may concern:

Be it known that I, FRANCIS H. SHEPARD, a citizen of the United States, and a resident of New Rochelle, in the county of West-
5 chester and State of New York, have invented a new and useful Improvement in Control Systems, of which the following is a specification.

My invention relates to control systems
10 for electric motors, and it has special reference to systems of control of the multiple unit type such as are employed for train operation upon large electrical railways and railroad electrifications.

15 One of the objects of my invention is to simplify and improve the arrangement of circuits and the operation of systems of the above indicated character, with particular reference to systems in which the control
20 apparatus and the auxiliary devices are supplied with energy indirectly from the trolley circuit.

Another object of my invention is to provide means for preventing improper operation and acceleration of the driving motors by reason of an accidental "cross" of the train line conductors, which energize the auxiliary apparatus, with those which supply energy to the control apparatus.

30 Another object of my invention is to provide a control system adapted for multiple unit train operation in which the control apparatus or unit switches and the auxiliary apparatus are adapted for operation upon materially different voltages.

35 A still further object of my invention is to provide a control system in which the auxiliary apparatus is operated from low-voltage train line conductors which are constantly energized, whereas the control apparatus receives its energy intermittently from relatively high voltage train line conductors, at the will of the motorman or attendant.

40 45 A still further object of my invention is to provide means for limiting the current in the control wires to a safe value in case a train bridges a break between adjacent sections of reversed polarity and both control
50 resistors are concurrently connected into active circuit.

In the prior art, when multiple unit train operation has been employed and the auxiliary apparatus and the control apparatus were both energized from circuits

having a common return conductor and at substantially the same voltage, difficulty has been experienced by reason of the "crossing" of the respective train line conductors. Such a condition results in an accidental 60 energization of the unit switches and consequent acceleration of the driving motors, which rendered them beyond the control of the motorman.

It will be understood that, even if the controller were in the "off" position and the auxiliary apparatus train conductors should accidentally come in contact with the conductors of the control apparatus, full operating voltage would be impressed upon 65 the operating coils thereof. Thus, the motor circuit switches would be closed and the driving motors operated. The liability of damage to the apparatus, as well as injuries to train passengers would then be great. 70

Moreover, in certain classes of electrified railway systems, particularly where two supply conductors deliver direct current energy to the motors and auxiliary circuits, the corresponding conductors of adjacent 80 and insulated sections are frequently of opposite or reversed polarity. Under these conditions, if a train is partly on one section and partly on another, and control apparatus on both sections should be operated at 85 the same time, a dead short circuit through the train line conductors might result which might destroy said conductors or at least, impair the proper functioning thereof, unless adequate protective measures were em- 90 ployed.

It is with the intention of eliminating the possibility of such difficulties that I have devised my present invention.

In the accompanying drawing, Figure 1 95 is a diagrammatic view of a control system embodying my invention in which only a single section of supply conductors and a single car equipment are shown, Fig. 2 is a diagrammatic view showing a modification 100 of certain of the connections shown in Fig. 1 and Fig. 3 is a diagrammatic view of a two-car train embodying my control system.

Referring to the drawing, the system here shown comprises a plurality of supply conductors 1 and 2 of opposite polarity and which constitute parts of a single section, a plurality of electric motors having armatures A^1 and A^2 and field magnet windings F^1 and F^2 , a plurality of resistors R^1 , R^2 , 110

and R^3 and a corresponding number of short-circuiting switches for eliminating said resistors from circuit, a line switch LS, an electro-responsive device marked "Limit switch," a hand-operated switch device marked "Controller," a "control resistor" adapted to be connected across the supply circuits by means of "control switch #1" and "control switch #2," a plurality of control circuit conductors marked "Train lines," and a plurality of translating devices 10, 11 and 12 which may, for example, respectively constitute electro-pneumatic apparatus for governing the operation of the car doors or 15 couplers, and conductors' signal lamps and bells.

In order to simplify the diagram and to enable a ready and clear understanding of the operation of my invention, I have illustrated it in connection with a series arrangement of driving motors, but it should be understood that my invention is in no way restricted to such connections and is applicable to many of the well-known types of 25 systems.

Assuming the circuit connections and apparatus to occupy the positions shown, the operation of the system is as follows:

If "control switches" #1 and #2 be 30 closed, the "control resistor" is connected directly across the supply circuits and therefore energized. The "control resistor" is provided with a plurality of taps or conductors, 13, 14, and 15, tap 14 being connected to said "resistor" at substantially its mid point. The connections of the conductors 13 and 15 to the "resistor" are so chosen that the voltages between said conductors 13 and 15 and the common conductor 14 differ widely, for a purpose to be 35 hereinafter set forth.

As soon as the "control resistor" is energized, low-voltage is impressed upon "train lines" 16 and 17 which are constantly energized thereafter and which serve to supply 40 energy to the translating devices 10, 11 and 12 when switches 10^s, 11^s, and 12^s are closed.

If the "controller" be moved to its first operating position, a circuit is completed 45 from tap 13 through conducting segments 20 and 21 of the "controller," "train line" 22, energizing coil of switch LS, and the common return conductor 16 to the mid-point tap 14 of the "control-resistor." Thus, 50 energy is supplied to the operating coil of switch LS at a relatively high voltage compared to that impressed across "train line" conductors 16 and 17.

Switch LS is thus closed to complete a circuit from supply conductor 1, including 55 switch LS, energizing coil of the "limit switch," resistors R^1 , R^2 , and R^3 , and the armatures and field magnet windings of the driving motors to supply conductor 2.

60 Energy is thereby supplied to the driving

motors and they are accordingly started into operation.

Without reciting in detail the operation of the system and tracing its circuits, it is believed that no difficulty will be experienced in understanding that if the "controller" be removed to its next operating position, the resistors R^1 , R^2 , and R^3 will be short-circuited by their corresponding switches in accordance with the well-known 75 action of the "limit switch."

When the "controller" is moved to its second position, "train line" 23 is energized from the "control resistor" through tap 13 and conducting segments 20 and 21 of the 80 "controller." Thereafter, the operation is automatic in a manner old and familiar to those skilled in the art.

Referring particularly to the "train line" conductors, it will be noted that conductors 85 16 and 17 are energized constantly and that a comparatively low-voltage exists between them, whereas conductors 22 and 23 are only energized upon the operation of the "controller," and a materially greater voltage is 90 impressed between them and the common return conductor 16.

If now, the energizing coils of switches LS, R^1 , R^2 , and R^3 are designed for operation upon the relatively high voltage between taps 14 and 13, and if "train lines" 95 22 or 23 be accidentally "crossed" with conductor 17, it will be impossible to effect the closure of any of the motor-accelerating switches above referred to, inasmuch as the 100 low-voltage between taps 14 and 15 is insufficient for the purpose.

The possibility of accidental operation of the motor switches and the acceleration of the driving motors is therefore precluded, 105 and safety and reliability are assured.

Likewise, whenever the train passes over a section break, where corresponding supply conductors are of reversed polarity, no serious damage to the train lines and control 110 conductors can result in the event that the control resistors of cars upon different sections are concurrently connected in active circuit for the reason that the portions of said resistors between taps 13 and 14 and 115 their respective ends will be included in circuit to limit abnormal current.

This portion of my invention may best be understood by reference to Fig. 3 of the accompanying drawing in which cars C¹ 120 and C², constituting a two-car train, are so located with respect to section-break 30 as to bridge across the adjacent sections of supply-circuit conductors 1 and 1' and 2 and 2', the adjacent sections being of reversed 125 polarity, as indicated in the figure by the plus and minus signs.

The control resistor of car C¹ is connected across the conductors 1 and 2 and current-collecting devices 31 are adapted to make 130

traveling electrical engagement with the supply-circuit conductors. The conductors 13, 14, 15, 22 and 23 are connected in the manner hereinbefore set forth in connection 5 with Fig. 1.

The apparatus and circuit connections of car C² are similar in every respect to those of car C¹ whereby multiple-unit operation may be effected.

10 Assuming that the train bridges the section break as shown in Fig. 3 and that, for some reason, the control switches on both cars are closed and the controllers consequently operated, as might be the case, for 15 instance, when an operator is "changing ends" of his train. Under these conditions, a circuit is established from the positive supply conductor 1 through collecting devices 31, control switch #1, end section of 20 the control resistor, conductor 15, train-line conductor 17, corresponding end section of the control resistor of car C² and its control switch and collecting devices to the negative supply-circuit conductor 1'.

25 Similarly, another circuit is established from the negative supply-circuit conductor 2 through current-collecting devices 31, control switch #2, end section of the control resistor of car C¹, conductor 13, the train-line conductor 22, the controller of car C², conductor 13, end section of the control resistor of car C² and thence, through the corresponding control switch and current-collecting devices, to the positive supply circuit 30 conductor 2'.

35 If such circuit conditions should obtain, it is clear that dead short circuits through the train line conductors are not affected by reason of the inclusion of the respective 40 end sections of the control resistors which prevent the flow of excessive current. In this way, therefore, accidental difficulties of the type referred to are obviated and the system is rendered reliable and effective, 45 even under these unusual conditions.

In certain cases where the track rails are employed as return conductors, the auxiliary taps 13, 14 and 15 will be arranged and connected to the "control resistor" in the 50 manner shown in Fig. 2, there being no necessity in this case that the common return conductor 14 be connected to substantially the mid-point of the "resistor".

Other modifications in the arrangement of 55 circuits and apparatus are contemplated and only such limitations should be imposed as are indicated in the appended claims.

I claim as my invention:

1. In a control system, the combination 60 with a supply circuit, a dynamo electric machine, control apparatus for governing the operation thereof, and an auxiliary translating device, of a derived source of energy associated with said supply circuit and having a 65 plurality of taps for energizing said control

apparatus and said translating device, only one of said taps being common to both energizing circuits.

2. In a control system, the combination 70 with a supply circuit, a dynamo electric machine, control apparatus for governing the operation thereof, and an auxiliary translating device, of a derived source of energy associated with said supply circuit, a plurality of circuits connected thereto for respectively energizing said control apparatus and said translating device, said circuits having only a single common conductor.

3. In a control system, the combination 75 with a supply circuit, a dynamo electric machine, control apparatus for governing the operation thereof, and an auxiliary translating device, of a derived source of energy associated with said supply circuit, a plurality of circuits of materially different voltages 80 connected thereto for respectively energizing said control apparatus and said auxiliary translating device.

4. In a control system, the combination 85 with a supply circuit, a dynamo-electric machine, control apparatus for governing the operation thereof, and an auxiliary device, of a derived source of energy associated with said supply circuit, a plurality of circuits of materially different voltages connected thereto for respectively energizing said control apparatus and said auxiliary translating device and having a common return conductor.

5. In a control system, the combination 90 with a supply circuit, a dynamo-electric machine, control apparatus for governing the operation thereof, and an auxiliary translating device, of a derived source of energy associated with said supply circuit, a plurality of circuits of materially different voltages, the circuit of higher voltage being adapted 95 to energize the control apparatus and the circuit of lower voltage being adapted to energize said translating device, and a conductor serving in common for both circuits.

6. In a control system, the combination 105 with a supply circuit, a dynamo electric machine, control apparatus for governing the operation thereof, and an auxiliary translating 110 device, of a derived source of energy associated with said supply circuit, a conductor connected to the mid-point of said derived source and serving in common for two circuits that are respectively adapted to energize said control apparatus and said translating device, the other conductors of said circuits being connected to the derived source at opposite sides of said common conductor and at different distances therefrom, 115 whereby the voltages of said circuits differ materially.

7. In a control system, the combination 120 with a supply circuit, a dynamo-electric machine, control apparatus for governing the 125

operation thereof, and an auxiliary translating device, of a derived source of energy associated with said supply circuit, a conductor connected to substantially the mid-point thereof, and other conductors connected to said derived source on opposite sides of said first conductor and severally adapted, in conjunction with said first conductor, to constitute energizing circuits for said control apparatus and said translating device.

8. In a control system, the combination with a supply circuit, electric apparatus receiving energy therefrom, means for controlling the operation of said apparatus, and other translating means, of a derived source of energy associated with said supply circuit, and a three-wire energizing system connected thereto and having materially different voltages between its common and respective outer conductors for supplying energy to said control means and said translating means.

9. In a control system, the combination with a supply circuit, a plurality of electric devices adapted to be operated upon materially different voltages, and a derived source of energy connected across said supply circuit, of a plurality of energizing circuits connected thereto and having a common conductor for supplying energy to said electric devices, said circuits being of suitable voltages to operate the devices connected thereto.

10. In a control system, the combination with a supply circuit, an electric motor, control apparatus therefor adapted to be energized intermittently, and an auxiliary translating device adapted to be constantly energized, of a resistor connected across said supply circuit, and a plurality of energizing circuits of different voltages connected thereto and having a common return wire, the circuit of higher voltage being adapted to energize said control apparatus and the circuit of lower voltage being adapted to energize said translating device.

11. In a system of control, the combination with a supply circuit, an electric motor connected thereto, control apparatus for governing the operation thereof, and a translating device, of a resistor connected across said supply circuit, a plurality of conductors connected to said resistor, one of said conductors constituting a part of an energizing circuit for said control apparatus and adapted to be manually interrupted and the other conductor constituting a part of the energizing circuit for said translating device and adapted to be energized constantly, and a third conductor connected to said resistor intermediate said first conductors and at unequal distances therefrom and serving as a return conductor for both of said first conductors.

12. In a control system, the combination

with a supply circuit, an electric motor, control apparatus therefor, an auxiliary translating device, of a control resistor connected across said circuit, and a plurality of train line conductors connected thereto and adapted to independently energize said control apparatus and said translating device, and a train line conductor connected to said control resistor intermediate said first conductors and serving to complete the energizing circuits thereof.

13. In a control system, the combination with a supply circuit, a dynamo-electric machine, control apparatus for governing the operation thereof, and an auxiliary translating device, of an auxiliary source of energy, and a plurality of control circuits of materially different voltages connected to said auxiliary source of energy for respectively energizing said control apparatus and said auxiliary translating device.

14. In a control system, the combination with a supply circuit, a dynamo-electric machine, control apparatus for governing the operation thereof, and an auxiliary translating device, of a plurality of control circuits of materially different voltages for respectively energizing said control apparatus and said auxiliary translating device.

15. In a control system, the combination with a dynamo-electric machine, electro-responsive control apparatus for governing the operation thereof, and an auxiliary electrical device, of circuits of different voltages for respectively supplying energy to said machine, said control apparatus and said auxiliary device.

16. In a control system, the combination with a supply circuit, a dynamo-electric machine adapted to receive energy therefrom, electrically controlled switches for governing the operation thereof, and an auxiliary electrical translating device independent of the machine and its operation, of a master controller and a plurality of train-line conductors for governing the operation of said control switches, other train-line conductors adapted to be connected to said auxiliary device and means for supplying voltages of materially different values to the control switch train-line conductors and to the auxiliary device train-line conductors.

17. In a control system, the combination with a dynamo-electric machine, control switches for governing the operation thereof, and auxiliary translating means independent of the machine and its operation, of a source of energy, and a plurality of conductors connected to different points thereof, the voltages between the intermediate conductor and the respective outer conductors being materially different and the outer conductors of the respective circuits being connected to the respective control switches and to the auxiliary means.

18. In a control system, the combination with a dynamo-electric machine, a plurality of control switches for governing the operation thereof, and an auxiliary translating device independent of said machine and its operation, of a plurality of energizing circuits of materially different voltages respectively connected to the control switches and the auxiliary devices, said circuits having a single common conductor.
19. In a direct-current control system, the combination with a pair of supply circuit conductors of opposite polarities and having sections upon which the polarities are reversed, of an electrically propelled vehicle adapted to receive energy therefrom and comprising a control resistor adapted to be connected across the pair of supply circuits and a pair of train lines connected to intermediate points in the central portion of said resistor.
20. In a direct-current control system, the combination with a plurality of adjacent and insulated sections of double supply circuit conductors, the sections being of reversed polarities, of a plurality of train units severally adapted to receive energy independently from the supply conductors of the section upon which it is operated and each comprising an auxiliary control resistor, switching means for connecting said resistor across the supply conductors, and a plurality of train lines extending throughout the train and respectively connected to taps in each of said resistors, the taps being located in the central portions of the resistors, whereby the end portions thereof are maintained in circuit to limit the current if the train bridges a break in the adjacent sections of reversed polarities and the resistors upon train units occupying adjacent sections are concurrently connected to the supply conductors.
21. In a direct-current control system, the combination with a plurality of adjacent insulated sections of double supply-circuit conductors and of reversed polarities, of a plurality of electric vehicles constituting a train, and each comprising a resistor adapted to be connected across the supply-circuit conductors of the section upon which it is operated, a plurality of conductors connected to intermediate points of said resistor, a controller in circuit with one of said conductors, and a corresponding number of train lines respectively connected to said conductors throughout the train.
22. In a direct-current control system, the combination with a plurality of adjacent insulated sections of double supply-circuit conductors and of reversed polarities, of a plurality of electric vehicles constituting a train, and each comprising a control resistor,
- means for connecting said resistor across the supply-circuit conductors of the section upon which the vehicle is operated, a plurality of train lines throughout the train and severally connected to a plurality of intermediate taps in said resistor, one tap being at the substantial mid-point of said resistor, and the others on opposite sides thereof and removed materially from the respective ends thereof, and a controller connected in circuit between one of said train lines and one of the outer taps of said resistor whereby the portions of the resistors between the outer taps and the supply circuit conductors limit the current when the train bridges a break between adjacent sections of the supply-circuit conductors of opposite polarity and the resistors are connected in circuit.
23. In a control system, the combination with a supply circuit, a dynamo-electric machine, control apparatus for governing the operation of said machine, and an auxiliary translating device, said translating device being sensitive to currents of a lower voltage than said control apparatus, of an auxiliary source of energy and a plurality of control circuits of materially different voltages connected to said auxiliary source of energy for respectively energizing said control apparatus and said auxiliary translating device.
24. In a control system, the combination with a supply circuit, a dynamo-electric machine, control apparatus for governing the operation of said machine, and an auxiliary translating device, the translating device and the control apparatus being sensitive to currents having voltages of different values, of a plurality of control circuits of materially different voltages for respectively energizing said control apparatus and said auxiliary translating device.
25. In a control system, the combination with a supply circuit, a dynamo-electric machine, control apparatus for governing the operation of said machine, and an auxiliary translating device, the translating device and the control apparatus being sensitive to electrical energy having different characteristics, of a plurality of control circuits conducting electrical energy having different characteristics for respectively energizing said control apparatus and said auxiliary translating device.

In testimony whereof, I have hereunto subscribed my name this 16th day of December 1913.

FRANCIS H. SHEPARD.
